VALVE ACTUATING MECHANISM FOR
BARREL-TYPE ENGINES

Marius Georges Henri Girodin, 20 Place de la Madeleine,
Paris, France

Filed Apr. 20, 1962, Ser. No. 139,066
4 Claims. (Cl. 123—58)

This invention relates to a timing system for barrel-type engines, that is for engines of the type wherein a plurality of cylinders are arranged in substantially parallel relation around a power output shaft, and wherein the pistons are articulated through rods on the periphery of a swivel member which, due to its wobbling motion, imparts rotary motion to the shaft.

The application of conventional technology to the arrangement of the timing system of such a barrel-type engine, particularly of the type in which each cylinder constitutes a four-stroke engine, leads to the utilization of numerous and complicated parts and also to gas passages of complex forms.

This invention obviates these disadvantages.

According to the invention the timing is effected with the aid of a single assembly, mounted as a whole at the end of the engine on the cylinder head side, including a cam-shaft mounted coaxially relatively to and receiving its movement from the power output shaft of the engine.

The cam-surfaces of the cam-shaft cooperate with push-rods disposed radially, in a plane normal to the engine shaft and the push-rods, actuating organs having the same function (admission or exhaust or starting or pump valves), may be disposed according to a regular polar symmetry around the power output shaft.

In large engines, the pumps may be disposed radially and mounted symmetrically at the end of the corresponding push-rods;

The gas arrives radially at the combustion chambers or admission valve chests through radial passages disposed according a polar symmetry and arrives axially at these radial distribution passages by passing axially through the timing block around the cam-shaft.

Radial passages are provided for the push-rods and fluid-tight joints are provided for each radial push-rod.

Such a timing block may be mounted removable and secured to the engine housing for example by a crown of bolts.

A distribution block according to the invention is light, easily machined, and easy to fit. It is particularly well adapted to supercharging.

Other characteristics of the invention will appear from the following description, given solely by way of example and with reference to the accompanying drawings, in which:

FIGURE 1 is a sectional elevation view of the invention, and

FIGURE 2 is a partial sectional and plan view of the invention taken along line 2—2 of FIGURE 1.

In FIGURES 1 and 2 the timing block is illustrated for a barrel-type engine having nine cylinders.

The engine itself is not represented, owing to the fact that any conventional engine, of the type referred to, may be provided with a timing assembly according to the invention—it may be indicated that an engine of said type is disclosed in my Patent Number 2,702,483 which is included herewith by way of reference.

The casing of the timing assembly is formed by a single piece constituted by two cylinders co-axial with the power output shaft 8: the outer cylinder 1 which carries a fastening flange 2 and the inner cylinder 3.

2

These axial cylinders 1 and 3 are connected by radial cylindrical passages, of which there are nine symmetrically distributed in a plane perpendicular to the axis for each function and each of which contains the corresponding push-rod. Four sets of nine push rods are provided, namely a set for the admission valves, a set for the exhaust valves, a set for the starting valves, that is the valves for the admission of compressed air for the starting of the engine and a set for the valves of the pumps.

10 The air for combustion passes between the cylinders 1 and 3 and the said thirty-six radial passages.

The central support hub 4 is fixed by a flange 5 on the inner cylinder 3 of the casing. This hub 4 supports internally, through the bearings 6 and 7, the central power output shaft 8 turning at the speed of the engine shaft and driven by the engine shaft through the medium of a suitable coupling, here by the splining means 9. The power output shaft 8 carries the gear tooth 10 meshing with the large gearwheel of the lateral gear train 11.

15 The central fixed hub 4 carries externally, through bearings 12 and 13, a crown 14 driven by its internal tooth 15 meshing with the small wheel of the lateral train 11.

20 In the example, three lateral trains such as 11 are illustrated.

25 The crown 14 is formed as a hollow shaft and carries four cam plates suitably keyed on it: the four-cam plate 16 controlling the push rods 17 controlling the compressed air starting valves; the four-cam plate 18 controlling the exhaust valves through the rollers 19 and the push rods 20; the four-cam plate 21 controlling the admission valve bent rockers 24 through the rollers 22 and the push rods 23; the four-cam plate 25 controlling the injection pumps 27 through the push-rods 26 which are adjustable at their extremities.

30 The air arriving through the manifold 28, either from a filter or from a supercharging blower, passes between the co-axial cylinders 1 and 3 in the intervals between the 36 radial passages guiding the push-rods and passes through the nine apertures 29, where the inlets 30 of the cylinder heads are connected by means of self-directing gaskets 31.

35 The push-rods 20 and 23 of each combustion chamber are connected in a fluid-tight manner in each corresponding passage and pass through the casing in a common aperture, where the housing of the rockers is connected by means of self-adjusting gaskets 32.

40 The operation of a timing system of this type according to the invention is obvious to those versed in the art and therefore need not be described.

45 The example described corresponds to an engine of medium or high power. For smaller dimensions, the timing casing and the cylinder heads can advantageously form a single piece.

50 What I claim is:

55 1. A distributing device for a motor with a power output shaft and a block of several cylinders each having a cylinder head, said cylinders being spaced in regular manner around the power output shaft, said distributing device comprising a cam shaft coaxial to said power output shaft, said cam shaft being located in a cylindrical casing and coaxial with said power output shaft, said casing being constituted of two cylinders of which one cylinder is received inside the other cylinder, the interval between the said cylinders constituting a passage for the in-take air, said casing and cam shaft constitute an assembly which is removable with respect to said cylinder block.

60 2. A device according to claim 1 wherein said interval leads directly into the cylinder head of each cylinder.

3. A device according to claim 1 wherein each cam is made up of a separate plate which is fixed on said cam shaft, and hollow sleeves are provided and are disposed radially, a set of push members coacting with cams of said cam shaft, said sleeves allowing the push members which are controlled by said cams to traverse said two cylinders of said casing to reach the respective cylinder heads without disrupting said passage for intake air.

4. A device according to claim 1, wherein said cam shaft is hollow and is supported by the intermediary of a hollow sleeve fixed relative to said cylindrical casing, said fixed sleeve being disposed inside said hollow shaft.
